F. G. CREED

TELEGRAPHIC APPARATUS FOR THE AUTOMATIC RECEPTION
AND RETRANSMISSION OF ELECTRIC SIGNALS

4 Sheets-Sheet 1

The drawing illustrates a complex mechanical assembly, likely a valve or actuator, with numerous labeled components. The main body of the device is labeled with the letter *z*. Key parts include:

- Top section: A lever system with a spring, labeled with numbers 1 through 16 and letters *a* through *z*. A small motor or actuator is shown at the top left.
- Middle section: A vertical rod labeled *u* and *u'* with a valve component labeled *u*.
- Bottom section: A large cylindrical component labeled *u* and *u'*.
- Electrical circuit: A separate diagram on the right shows a battery with terminals *+* and *-*, connected to a switch labeled *z* and a coil labeled *z*.

UNITED STATES PATENT OFFICE.

FREDERICK GEORGE CREED, OF CROYDON, ENGLAND.

TELEGRAPHIC APPARATUS FOR THE AUTOMATIC RECEPTION AND RETRANSMISSION
OF ELECTRIC SIGNALS.

Application filed April 12, 1924. Serial No. 706,023.

To all whom it may concern:

Be it known that I, FREDERICK GEORGE CREED, a subject of the King of Great Britain and Ireland, residing at Croydon, in the county of Surrey, England, have invented Improvements in or Relating to Telegraphic Apparatus for the Automatic Reception and Retransmission of Electric Signals, of which the following is a specification.

10 This invention has reference to that type of telegraphic apparatus for the automatic reception and re-transmission of electric signals, wherein the signals received by one line or section of a line are caused to dis-
15 place, in an endways direction, successive parallel pins or equivalent devices that are carried by a movable member and caused to move in an endless path, such pins, ac-
cording to their endways position, enabling
20 corresponding signals to be re-transmitted over a second line or section of line, each of the pins, after being displaced by the action of a signal and utilized for transmitting the signal to the second line or section of line,
25 being restored to its original position for reuse. In such apparatus the pins have sometimes been carried by an endless chain and sometimes by a rotary wheel.

Now the present invention has reference
30 to improvements in telegraph apparatus of the type referred to and it has for its ob-
ject to simplify the construction and oper-
ation of such apparatus and to enable the ap-
paratus automatically to compensate for any
35 distortion of the received signals in such a manner that the signals can be re-transmit-
ted or repeated in as steady and regular a manner as can be done with a standard Wheatstone transmitter or other transmitter
40 of the Wheatstone type.

To this end, the endways movable parallel pins are caused to move in an endless path by a wheel (hereinafter called for distinction the pin wheel) driven through a friction clutch from a shaft that is caused to rotate as nearly as possible at a predetermined rate and the position of which wheel in a rotary sense, to compensate for distorted signal is capable of being adjusted by one or more correcting wheels connected to the pin wheel and adapted to be operated, when this may be necessary, by one or more correcting devices usually in the form of a rod or rods. The pins are each moved lat-
50 erally in one direction by one or other of two

operating members (hereinafter called for distinction tappers), or it may be by a single tapper, the correcting device or devices and the tappers or tapper forming part of telegraph receiving apparatus that is under the control of the electric signals that are to be received and retransmitted. Such telegraph receiving apparatus may advantageously be constructed, operated and electrically controlled in the manner described in the specifications of British Letters Patent Nos. 204,398, 165,821, 165,820, 23,834 of 1908, 5,490 of 1905, 1,061 of 1902, and 2,834 of 1901, the two punches, forming part of such receiving apparatus for perforating tape in accordance with the signals received, being replaced by devices, such as levers, adapted to act as tappers, or by a single tapper for moving the pins endways in the required direction, in accordance with the received signals. The correcting wheel or wheels and correcting device or devices are or may be similar to the correspondingly named parts used in the said former apparatus, whilst the pin wheel corresponds to the tape feed wheel of such apparatus. Telegraph receiving apparatus of the kind described in the specifications of the said former Letters Patent is well known as a "Creed receiver" and will hereinafter for brevity, be so called.

The re-transmitting portion of the apparatus according to the present invention comprises two circuit controlling levers (hereinafter called for brevity and distinction A and B) each having an arm or part (hereinafter called for brevity and distinction, arm *a* or *b*) adapted to be moved by spring pressure in a direction towards the pins (hereinafter called signal pins) moved endways by the tappers controlled by received electric signals, and means for positively moving each of the said levers A and B with arms *a* and *b* in the opposite direction against the action of the springs. The arm *a* of lever A is adapted to be moved towards the signal pins moved by the tapper that is under the control of signals, due say to a positive or marking current, and the arm *b* of lever B is adapted to be moved towards the signal pins that are moved by the tapper that is under the control of signals due to a negative or spacing current. The arrangement is such that when a signal pin is moved endways by one tapper, under

the control of a positive current, so as to move its corresponding end out of the path of the adjacent arm *a* of the corresponding lever *A*, such arm, when relieved of the action of its positive operating means, will be moved by its spring across the path of the said pin to a sufficient extent to enable the lever *A* to close a circuit for transmitting a positive current to the second line or section of line and when the other tapper moves a signal pin endways, under the action of a negative current, so as to move its corresponding end out of the path of the adjacent arm *b* of the second lever *B*, such arm, when relieved of the action of its positive operating means, will be moved by its spring across the path of the corresponding signal pin to a sufficient extent to enable the said second lever to close a circuit for transmitting a negative current to the said second line or section of line. The function of the circuit controlling levers *A* and *B* is similar to that of the rocking bell crank levers in a standard Wheatstone transmitter for sending from a local battery positive and negative signals; and the function of the arms *a* and *b* thereof, that move across the path of the signal pins, is similar to that of the peckers in a Wheatstone transmitter, the absence or presence of pin ends in the path of the lever arms, corresponding to the absence or presence of perforations in a Wheatstone-Morse or other perforated tape passing through a Wheatstone transmitter. The alternate movements of the levers *A* and *B* therefore act to send positive and negative currents to the second line or section of line.

Automatic receiving and re-transmitting apparatus embodying the invention can be variously constructed.

In the accompanying illustrative drawings, Figs. 1 and 2 show respectively in side elevation and plan, one construction of telegraph apparatus according to the invention, suitable for the automatic reception and re-transmission of Wheatstone-Morse electric signals. Fig. 3 shows the apparatus partly in side elevation and partly in longitudinal section on the line III-III of Fig. 2. Fig. 4 is a cross section on the line IV-IV of Fig. 1 and Fig. 5 is a cross section on the line V-V of Fig. 3. Fig. 6 is a perspective view of pin restoring cams. Figs. 7 and 8 show respectively in side elevation and plan, part of a pin chain according to the invention, suitable for the reception and re-transmission of Wheatstone-Morse or cable code signals, part of the chain shown in Fig. 7 being in longitudinal section on the line VII-VII of Fig. 8. Fig. 9 is a cross section on the line IX-IX of Fig. 7, Fig. 10 is a similar view to Fig. 9 but showing the pins in a different position. Fig. 11 shows one of the links of the chain in longitudinal section. Fig. 12 is a detail view to

a larger scale than Figs. 1, 2 and 3. Fig. 13 shows in side elevation and Fig. 14 in cross section on the line XIV-XIV of Fig. 13, part of a modified construction of pin chain suitable for use in Wheatstone-Morse, or cable code working. Figs. 15, 16 and 17 show part of the said pin chain in plan with the signal pins in three different positions in the three figures. Fig. 18 is a similar view to Fig. 5 but shows a modified arrangement. Figs. 19 and 20 show in plan, part of a chain like that shown in Figs. 13 and 14 adapted for use when working according to the five unit or other multiple unit code. Fig. 21 shows partly in plan and partly in horizontal section, means for moving the signal pins shown in Figs. 7 to 11 inclusive and in Figs. 13 to 17 inclusive, endways in their chain in accordance with received signals transmitted according to the cable code.

According to the arrangement shown in Figs. 1 to 12, in which two sets of signal pins *a* and *b* are carried by an endless chain *c*, the chain passes around and is driven by a toothed wheel *d* (herein called the pin wheel) fixed on a spindle *e* driven through a friction clutch and worm gearing at *f* from a main driving shaft *g* forming part of a Creed receiver, the chain also passing around a toothed wheel *h* fixed on a spindle *i* forming part of the re-transmitting apparatus and driven from the said main driving shaft *g* through worm gearing at *j*. The endless chain *c* comprises a number of links *c*¹ of loop shape as seen in plan (Fig. 8) and of L shape as seen in side elevation (Fig. 7), the two free ends of each link being inset at *c* so that they can enter and fit between the connected ends of the next link in the chain (see Figs. 8 and 9). For apparatus such as is now being described, suitable for the Wheatstone-Morse code, the side portions of each link, constituting the vertical arm of the link, has two sets of superposed holes for the reception of two horizontal signal pins *a* and *b* and the side portions of each link, constituting the horizontal arm of the link, are formed with one set of holes *c*³. The links are jointed together to form an endless chain by the lower signal pin *b* of each pair of signal pins *a* and *b*, passing through the lower hole in the vertical arm of one link *c*¹ and through the holes *c*³ in the horizontal arm of the next link, the lower portion of the end connecting member between the two side portions of each link being cut away as shown at *c*⁴ (Fig. 11), to admit of the passage therethrough of the horizontal arm of the adjacent link. The chain thus comprises a number of small L shaped links *c*¹ carrying a number of pairs of superposed signal pins *a* and *b*, each of the pins being free to move endways in its link. The two signal pins *a* and *b* of each pair represent respectively the positive and

negative elements of a signal and each pin has two lateral positions, one operative (see Fig. 9) and the other inoperative (see Fig. 10). The two pins *a* and *b* in each set are partly embraced, inside the link carrying them, by a bent spring metal plate *k* that serves to hold each pin frictionally in each endways position into which it is moved. The signal pins are operated by tappers *m*, *n* (Figs. 1 and 2) in the form of lever arms pivoted at *m*¹ and *n*¹ respectively, and positively moved at the required times into the operative and inoperative position by rods *o* and *p* respectively which are jointed to other arms *m*² *n*² connected to the tapper arms, the said rods being operated at the required times by the rotary double cam device *r* of a Creed receiver constructed and operated substantially as described in the specification of the said former British Letters Patent No. 165820. The said rods *o* and *p* replace the punches used in that apparatus and the toothed wheel *d* for driving the endless chain *c* carrying the signal pins *a* and *b*, takes the place of the tape feed wheel of such apparatus and has combined therewith the corrector wheels *d*¹, *d*² and corrector rods *s*, *s*¹ of the said Creed receiver. The tappers *m* and *n* may, as shown, be arranged at opposite sides of the chain *c* so that one of them, say *m*, will move the pins *a* representing positive signals, laterally in one direction from the position shown in Fig. 9 to that shown in Fig. 10 and the other tapper *n* will move the other pins *b*, representing negative signals, laterally in the opposite direction from the position shown in Fig. 9 to that shown in Fig. 10. Both sets of signal pins *a* and *b* can be restored to their normal positions by stationary cams *t* and *t*¹ (see Fig. 6) between which the pin chain *c* passes after the pins have been used in the retransmitting portion of the apparatus.

The driving shaft *g* receives motion from an electric motor *u* (Fig. 1) and transmits motion through gearing *v* and a friction clutch at *w*¹, to the spindle *w* to which the cam spindle *r* is fixed. The spindle *w* is arrested and released by an escapement comprising a tooth on the said spindle and a slide bar *x* that is reciprocated, in accordance with the signals received, by the armature *y* of a power relay *z* responsive to the telegraphic line signals in a manner well understood, the slide bar having two diametrically arranged detents so that the spindle *w* makes one half of a revolution each time it is released.

The re-transmitting portion of the apparatus comprises, in addition to the toothed wheel *h* around which the pin chain *c* passes, as hereinbefore described, two spring controlled levers *1*—*1*^a and *2*—*2*^a arranged parallel to one another. One arm, namely, *1* or

2 of each lever, carries a contact *3* or *4* adapted to co-act with a stationary but adjustable contact *3*^a or *4*^a and the other arm *1*^a or *2*^a is provided with a downwardly extending arm *1*^b or *2*^b, the arm *2*^b having a lateral pin *2*^c arranged near to the endless chain and below the path of the signal pins *b*. The two levers are arranged in vertical planes at opposite sides of the chain *c* (Fig. 4) whilst the downwardly extending arms *1*^b and *2*^b are arranged to move in an approximately radial direction with reference to the axis of the toothed wheel *h*, one arm being slightly in advance of the other. To enable the said downwardly extending arms *1*^b, *2*^b to yield, should they be acted upon sideways for any reason, by the signal pins *a*—*b*, each arm is jointed to its lever *1*—*1*^a or *2*—*2*^a and normally held in position by a spring *4* (Fig. 12). Associated with the two levers *1*—*1*^a and *2*—*2*^a and arranged between downwardly and upwardly extending bent parts *1*^d, *2*^d (Fig. 5) connected to them, is a vertically oscillating device, shown as a flat plate *5*, operated by a lever *6* connected to a rotary crank pin *7*, or eccentric, on the end of the shaft *g*. *8* is a spring connected to the arm *1* of lever *1*—*1*^a and *9* is a spring connected to the arm *2*^a of lever *2*—*2*^a. The arrangement is such that when the oscillating device *5* is moved upward, the arm *2*^a of lever *2*—*2*^a carrying the downwardly extending arm *2*^b with lateral pin *2*^c will be raised by the action of its spring *9*, and when the oscillating device *5* moves downward, the arm *1*^a of lever *1*—*1*^a with the downwardly extending arm *1*^b will be moved downwardly by the action of its spring *8*.

If a signal pin *a* or *b* corresponding to lever *1*—*1*^a or *2*—*2*^a has been displaced endways by its tapper *m* or *n*, the arms *1*^a, *1*^b or the arms *2*^a, *2*^b of the lever, when released, will, by the spring *8* or *9*, be caused to pass the end of the displaced pin to a sufficient extent to enable the lever to close the circuit of the second line or section of line through the contact *3*, *3*^a or *4*, *4*^a, and transmit to the second line either a positive or a negative current corresponding to the original positive or negative signal received.

For enabling the speed of the electric motor *u* used for rotating the main driving spindle *g* and the toothed wheels *d* and *h* around which the endless pin chain *c* passes, to be varied from time to time to maintain synchronism between the speed of the motor and the speed of the received signals, there may be employed a circuit making and breaking device comprising a wheel *10*, operated by the rising or falling of the lower portion of the chain *c* between the two toothed wheels *d* and *h*, and electric contacts *11*, *11*^a controlled by the said wheel, the device acting to vary or control the speed of the

- said electric motor, as required. In the example shown in Fig. 1, the electric motor u has a shunt field winding 12 in series with which is a resistance winding 13. 14 and 15 are spring blades carrying the contacts 11, 11^a respectively which are normally held apart when the speed of the motor is normal but when the speed rises above the normal and the wheel h feeds the chain c too fast, 10 the wheel 10 will be moved downward by its spring 16 and bring the two spring blade contacts 11—11^a together so as to short circuit the resistance winding 13 and thereby reduce the speed of the motor u .
- 15 If desired the two tappers m and n may be arranged at the same side of the chain and the endways position of the pins modified accordingly.

Figs. 13 to 17 inclusive, show a modified construction of chain wherein each of the loop shaped links c^1 is straight, instead of being of L shape, and is provided with two pin holes only, each provided with an endways movable signal pin a^1 , the pin carried 20 by one link serving to joint that link to the next adjacent link. The chain therefore carries only one row of parallel signal pins, instead of two rows of parallel signal pins as in Figs. 7 to 11 inclusive. This modified 25 form of pin chain can be used in telegraphic receiving and re-transmitting apparatus of the kind hereinbefore described with reference to Figs. 1 to 12 for setting the signal pins in accordance with signals transmitted according to the Wheatstone-Morse 30 code.

In this case however the tapper m operated by say positive signals, is caused to move alternate signal pins a^1 say the odd 40 numbered pins 1, 3, 5 and so on, endways in one direction from a middle position shown in Fig. 15, to one side of the chain as shown in Fig. 16, so as to permit the corresponding signal transmitting lever 1, 45 1^a to make its effective strokes for retransmitting the positive signals. Also, the tapper n , operated by say negative signals, is caused to move the other alternate signal pins a^1 numbered 2, 4, 6 and so on endways 50 in the opposite direction from their middle position as shown in Fig. 15, to the opposite side of the chain as shown in Fig. 17, so as to permit the corresponding signal transmitting lever 2, 2^a to make its effective 55 strokes for retransmitting the negative signals.

When working on the Wheatstone-Morse code, whether using a chain according to Figs. 7 to 11 or to Figs. 13, 14 and 15, one 60 of the connecting wheels d^1 , d^2 is adapted for use with signal pins corresponding to positive signals and the other for use with signal pins corresponding to negative signals.

A signal pin chain having a single row 65 of signal pins as in Figs. 13 to 17 inclusive can also be used for the retransmission of signals, when working with the five unit or other multiple unit code. In this case each signal pin has only two positions, all of them normally extending from one side of the chain, as shown in Fig. 19, so that they are normally in position for the retransmission of signals of one polarity, conveniently negative signals. In this case only one tapper, say m , corresponding to positive signals, for displacing signal pins endways to the opposite side of the chain as shown in Fig. 20 to permit of the retransmission of positive signals, is necessary. The chain 80 may be used in apparatus such as shown in Figs. 1 to 6 inclusive but, as stated, only one tapper say m is necessary only one correction wheel d^1 or d^2 and only one correcting rod s or s^1 are necessary. Also, the cam 85 spindle w is released only on the receipt of positive signals and is then caused to make a complete revolution in known way, or a succession of complete revolutions, if a number of positive signals are received in succession and being arrested on the receipt of a negative signal. Also the circuit controlling levers 1—1^a and 2—2^a and the means (Fig. 5) used for controlling such levers, are modified as shown in Fig. 18, to admit 90 of the lever arms 1^a and 2^a moving downward together towards the pin chain, when the movable member 5 moves downward.

The pin chain shown in Figs. 7 to 11 inclusive and also that shown in Figs. 13 to 17 inclusive, can also be used in telegraph receiving apparatus designed to be worked by signals transmitted according to the cable-code, for instance in telegraphic receiving apparatus of the kind described and shown in the specification of British Letters Patent No. 204,398 hereinbefore referred to. In this case, such receiving apparatus is modified by substituting for the tape feeding wheel a of that apparatus, a toothed wheel like d shown in Figs. 1, 2 and 3 hereinbefore described and the punches g and h of the former arrangement are replaced as shown in the accompanying Fig. 21, by members 17 and 18 that 105 are notched at their rear ends like the punches of the former arrangement and are jointed to lever arms 19 and 20 pivoted at 21 and 22 and provided with signal pin tappers m and n between which the signal pin 110 chain moves as in the arrangement shown in Figs. 1, 2 and 3. Each notched member, 17, 18 is moved forward by a transversely movable selector pin 23 carried by a reciprocating bar 24 operated by rotary cam mechanism under the control of a relay responsive to both positive and negative signals, the said selector pin 23 being moved trans-

versely into one extreme position by a link 25 operated by the armature of a relay when positive signals are received and into its other extreme position when negative signals are received, as described in the specification of the said former British Letters Patent No. 204,398. As will be understood, when the selector pin 23 is moved into one extreme position and the reciprocating bar 24 moves forward, owing say to the reception of a positive signal, the corresponding tapper say m , will move the corresponding signal pin a^1 endways in one direction, and successive signal pins a^1 will be moved endways in the same direction so long as positive signals are being received. When however a negative signal is received, the selector pin 23 will be moved transversely into its opposite extreme position in the reciprocating bar 24 by the last mentioned relay and the tapper n will be actuated to move the signal pin a^1 then in position, in the opposite direction, successive signal pins being moved in the same direction, so long as negative signals are being received. In this case also the circuit controlling levers 1-1^a and 2-2^a and the means for controlling such levers are modified, as shown in Fig. 18, to admit of the lever arms 1^a and 2^a moving downward together towards the pin chain.

As will be obvious, the details of construction of apparatus according to the invention can be variously modified to suit requirements.

35 What I claim is:—

1. In apparatus for the automatic reception and retransmission of electric signals, a telegraphic receiver comprising a pin wheel, a driving shaft, means for rotating said shaft at a predetermined substantially constant speed, a yielding driving connection between said pin wheel and shaft, correcting means for adjusting said pin wheel in a rotary sense when this may become necessary, an endless chain passing around and driven by said pin wheel, signal pins movable transversely in said chain, means for adjusting the relative endways position of said pins in said chain to correspond to received signals, means for returning displaced signal pins to normal position after being used, mechanism adapted to actuate the pin wheel adjusting means and the means used for adjusting the endways position of said signal pins and means under the control of electric signals to be received and retransmitted, adapted on receipt of a signal to bring said mechanism into operation at the required times to actuate the pin wheel adjusting means and the signal pin adjusting means, and a signal repeater comprising a wheel around which said chain passes, means for driving said wheel at the same speed as the aforesaid driving shaft and circuit controlling mechanism depend-
2. In apparatus for the automatic reception and retransmission of electric signals, a telegraphic receiver comprising a pin wheel, a driving shaft, a yielding clutch between said wheel and shaft, means for rotating said shaft at a predetermined substantially constant speed, a correcting wheel connected to said pin wheel, a correcting device adapted to engage said correcting wheel and adjust the pin wheel in a rotary sense when this may become necessary, an endless chain passing around and driven by said pin wheel, signal pins carried by said chain and movable transversely therein, a tapper for moving said pins endways in said chain to correspond to received signals, means for returning displaced pins to normal position after use, and mechanism under the control of the signals to be received and retransmitted, adapted to actuate the said correcting rod and tapper at the correct times, and a signal repeater comprising a wheel around which said chain passes, means for driving said wheel at the same speed as said driving shaft, and circuit controlling mechanism dependent for operation upon the relative endways position of the signal pins in the chain.
3. In apparatus for the automatic reception and retransmission of electric signals, a telegraphic receiver comprising a pin wheel, a driving shaft, means for rotating said shaft at a predetermined substantially constant speed, a yielding driving connection between said pin wheel and shaft, correcting means for adjusting said pin wheel in a rotary sense when this may become necessary, an endless chain passing around and driven by said pin wheel, signal pins movable transversely in said chain, means for adjusting the relative endways positions of said pins in said chain to correspond to received signals, means for returning displaced signal pins to normal position, rotary cams adapted when operated, to actuate the correcting means and the pin adjusting means, driving means arranged to operate continuously, a yielding connection between said cams and driving means, escapement mechanism one member of which is connected to the cams and a second member of which normally holds the first member and cams stationary and an electric relay responsive to the signal to be received and repeated, adapted on the receipt of a signal to cause the second escapement member, to release the first member and permit the cams to be rotated by said driving means, and a signal repeater comprising a wheel around which said chain passes, means for driving said wheel at substantially the same speed as the aforesaid driving shaft and signal repeating mechanism controlled by

the endways position of the signal pins in the chain.

4. In apparatus for receiving and re-transmitting electric signals, a telegraphic receiver comprising a pin wheel, a driving shaft means for rotating said shaft at a predetermined substantially constant speed, a yielding clutch between said pin wheel and shaft, a correcting wheel connected to said pin wheel, a correcting rod adapted when moved forward to engage said toothed wheel and adjust it and said pin wheel in a rotary sense when this may become necessary, an endless chain passing around and driven by said pin wheel, signal pins carried by said chain and movable transversely therein, a tapper adapted to move said signal pins endways in said chain from normal position into signal re-transmitting positions, a rod for moving said tapper into its operative and inoperative positions, means for returning displaced pins after use to normal position, a double rotary cam device for moving said correcting rod and tapper operating rod into their operative positions at the required times and afterwards returning them to normal position, driving mechanism adapted to run continuously, a yielding clutch between said cam device and driving mechanism, an escapement one member of which is connected to said cam device and a second member of which normally holds the first member and cam device stationary, and a relay responsive to signals to be received and re-transmitted, adapted on receipt of a signal to cause the second member of the escapement to release the first member and cam device and permit the cam device to be rotated by the driving mechanism and a signal repeater comprising a wheel around which said chain passes, means for driving said wheel at the same speed as the aforesaid driving shaft, and circuit controlling mechanism dependent for operation on the endways position of the signal pins in said chain.
5. In apparatus for receiving and re-transmitting electric signals, a telegraphic receiver comprising a pin wheel, a driving shaft, means for rotating said shaft at a predetermined substantially constant speed, a yielding clutch between said pin wheel and shaft, correcting wheels connected to said pin wheel, independent correcting rods adapted when moved forward to engage said correcting wheels and adjust them and said pin wheel in a rotary sense when this may become necessary, an endless chain passing around and driven by said pin wheel, signal pins carried by said chain and movable transversely therein, two tappers one adapted to move the signal pins in one direction from their normal position and the other to move said signal pins in the opposite direction from their normal positions, in-

dependent rods for actuating said tappers, means for returning displaced signal pins after use to normal positions, a double rotary cam device adapted when moved through one half a revolution to move one correcting rod and tapper operating rod into their operative positions and then return these rods to their normal position and upon the next half revolution to move the other correcting rod and tapper operating rod into their operative positions and then return these rods to their normal position, driving mechanism adapted to run continuously, a yielding clutch between said cam device and driving mechanism, and escapement one member of which is connected to said cam device and a second member of which normally holds the first member and cam device stationary, and a relay responsive to signals to be received and re-transmitted, adapted on receipt of a signal to cause the second member of the escapement to release the first member and cam device and permit the cam device to be rotated by the driving mechanism through half a revolution and then to re-arrest said first escapement member and cam device, and a signal repeater comprising a wheel around which said chain passes, means for driving said wheel at the same speed as the aforesaid driving shaft, and circuit controlling mechanism dependent for operation on the endways position of the signal pins in said chain.

6. In apparatus for the automatic reception and re-transmission of electric signals, a telegraphic receiver comprising a pin wheel, a driving shaft, means for driving said shaft at a predetermined substantially constant speed, a yielding clutch between said pin wheel and shaft, means for adjusting the pin wheel in a rotary sense when this may become necessary, an endless chain passing around and driven by said pin wheel, signal pins movable transversely in said chain, means for adjusting the relative endways position of said signal pins in said chain to positions corresponding to the signals received, electro-mechanically operated means adapted on the receipt of a signal, to move said pin wheel adjusting means and the means used for adjusting the endways position of the signal pins and then to return said means to normal position and means for returning displaced signal pins to normal position after use, and a signal repeater comprising a wheel around which said chain passes, means for rotating said wheel at substantially the same speed as said driving shaft and circuit controlling mechanism adapted to re-transmit received signals and dependent for operation or non-operation upon the absence or presence of signal pins in its path of movement.

7. In apparatus for the automatic reception and re-transmission of electric signals, a telegraphic receiver comprising a pin wheel, means for rotating the same, an endless chain passing around and driven by said pin wheel, signal pins arranged transversely to and carried by said chain, means adapted on the receipt of electrical signals, to displace signal pins endways in said chain to positions corresponding to the signals received, means for restoring displaced signal pins to their normal position after use and a signal repeater comprising a wheel around which said chain passes, means for rotating said toothed wheel at the same speed as the means used for rotating the pin wheel, and circuit controlling mechanism for re-transmitting signals corresponding to the received signals, said circuit controlling mechanism comprising levers, circuit connections controlled by movement of said levers for re-transmitting received signals, abutment devices arranged to be moved towards and from said signal pins by said levers, and means for oscillating said levers, the full movement of each lever being dependent upon the absence of a signal pin in the path of the corresponding abutment device.

8. For the automatic reception and re-transmission of electric signals, apparatus according to claim 7, in which the abutment device of each circuit controlling lever is pivoted to such lever and is held in its normal position by a spring adapted to enable it to be moved laterally when required.

9. In combined signal receiving and repeating apparatus, an endless chain, means for causing endways movement of said chain, signal pins mounted to move endways in a transverse direction in said chain, means for causing relative endways movement of said signal pins in accordance with received signals and circuit controlling means for repeating said signals, said circuit controlling means comprising abutment devices adapted to move towards and from said signal pins, means adapted to move said abutment devices towards and from said signal pins and to be arrested in one direction by signal pins in normal positions and circuit connections under the control of the means used for moving the abutment devices.

10. In combined signal receiving and repeating apparatus, an endless chain, means for causing endways movement of said chain, signal pins mounted to move endways in a transverse direction in said chain, means for causing relative endways movement of said signal pins in accordance with received signals and circuit controlling means for repeating said signals, said circuit controlling means comprising two abutment devices arranged to move towards and from said signal pins, two spring controlled levers adapted to move said abutment devices to their full

extent in the absence of signal pins in their path and circuit connections under the control of said levers.

11. In combined signal receiving and repeating apparatus, an endless chain, means for causing endways movement of said chain, signal pins mounted to move endways in a transverse direction in said chain, means for causing relative endways movement of said signal pins in accordance with received signals and circuit controlling means for repeating said signals, said circuit controlling means comprising two abutment devices arranged to move in directions at right angles to the length of the signal pins and across the ends of displaced pins, means for moving said abutment devices toward and from said signal pins, means adapted afterwards to move the abutment devices away from said signal pins and circuit connections under the control of the means used for moving said abutment devices towards said pins.

12. In combined signal receiving and repeating apparatus, an endless chain, means for causing endways movement of said chain, signal pins mounted to move endways in a transverse direction in said chain, means for causing relative endways movement of said signal pins in accordance with received signals and circuit controlling means for repeating said signals, said circuit controlling means comprises two independent levers, two separate abutment devices connected each to one end of one of said levers and arranged to move in a direction at right angles to the axis of each signal pin, springs each adapted to actuate one of said levers to move the associated abutment device towards a signal pin, means adapted to release each lever and permit it and its abutment device to be moved by its spring in the operative direction and afterwards to move said lever and abutment device into their inoperative positions, each lever making a full operative movement only when there is no signal pin in the path of its abutment device and circuit closing means under the control of said levers and adapted to close a circuit only when one or other lever makes its full operative movement.

13. In combined signal receiving and repeating apparatus, an endless chain, means for causing endways movement of said chain, signal pins mounted to move endways in a transverse direction in said chain, means for causing relative endways movement of said signal pins in accordance with received signals and circuit controlling means for repeating said signals, said circuit controlling means comprising two independent levers, two separate abutment devices connected each to one end of one of said levers and arranged to move in a direction at right angles to the axis of each signal

- pin, springs each adapted to actuate one of said levers to move the associated abutment device towards a signal pin, said levers being each provided with an extension, an oscillating device driven from the repeater and adapted to move from and towards each extension and permit the corresponding lever and abutment device to be moved in the operative direction by its spring and to positively move such parts into their inoperative position against the action of the associated spring, each lever making a full operative movement only when there is no signal pin in the path of its abutment device and circuit closing means under the control of said levers and adapted to close a circuit only when one or other lever makes its full operative movement.
14. In combined signal receiving and repeating apparatus, an endless chain, means for causing endways movement of said chain, signal pins mounted to move endways in a transverse direction in said chain, means for causing relative endways movement of said signal pins in accordance with received signals and circuit controlling means for repeating said signals, said circuit controlling means comprising two independent rocking spring controlled levers, abutment devices carried by said levers, and arranged to move in a direction at right angles to the axis of each signal pin, one abutment device terminating above the path of the pins and the other having an inturned extension terminating below the path of the pins, a spring connected to one lever and adapted to depress the abutment device terminating above a signal pin, a spring connected to the other lever and adapted to raise the abutment device having an extension below a signal pin, means for releasing the levers alternately to permit them to be moved by their springs in the operative direction and for moving them alternately against the action of their springs to normal position, each lever making a full operative movement only when there is no signal pin in the path of its abutment device, and circuit closing means under the control of said levers and adapted to close a circuit only when one or other lever makes its full operative movement.
15. For a combined signal receiving and repeating apparatus, a signal pin carrying chain comprising links of loop shape as seen in plan, the free end portions of each link being inset and fitted within and between the connected end portions of the link and endways movable signal pins extending through the overlapping end portions of adjacent links so as to joint said links together.
16. For a combined signal receiving and repeating apparatus, a signal pin carrying chain comprising links of loop shape as seen in plan, the free end portions of each link being inset and fitted within and between the connected end portions of the next link, endways movable signal pins extending through the overlapping end portions of adjacent links so as to joint said links together, and bent spring plates acting to hold said signal pins frictionally in an endways direction.
17. For combined signal receiving and repeating apparatus a signal pin carrying chain comprising links each consisting of two L-shaped side parts the vertical members of which are connected together at the top and the horizontal members of which are inset at their free ends and fitted between the side parts of the next adjacent link, the vertical members of each link having superposed holes therein and the free end portions of the horizontal members having single holes therein to align with the lower holes of the pairs of holes in the vertical members of an adjacent link and pairs of superposed signal pins extending through and endways movable in the superposed holes in the vertical members of each link, the lower pin of each pair also extending through the holes in the inset free ends of the horizontal members of the next adjacent link.

FREDERICK GEORGE CREED.
